CLAIM

The ornamental design for a lighting decoration, as shown and described.

DESCRIPTION

FIG. 1 is a perspective view of a lighting decoration design showing my new design;

FIG. 2 is a front view of FIG. 1;

FIG. 3 is a rear view of FIG. 1;

FIG. 4 is a left view of FIG. 1;

FIG. 5 is a right view of FIG. 1;

FIG. 6 is a top view of FIG. 1;

FIG. 7 is a bottom view of FIG. 1;

FIG. 8 is an enlarged view of the selected portion "8" in FIG. 2; and,

FIG. 9 is an enlarged view of the selected portion "9" in FIG. 6.

Any shading and cross-hatching are not features of the design but are utilized to illustrate the surface contours of the lighting decoration design in the drawings. The dash-dot-dash broken line defines the boundary of the enlarged views and form no part of the claimed design.
